BATHING CAP

Ernest Samuel Abram, Heaton Chapel, Stockport,
England, assignor of one-half to Harry Eva,
Stockport, England

Application October 25, 1934, Serial No. 749,887
In Great Britain July 3, 1934

1 Claim. (Cl. 2-68)

This invention refers to bathing and like caps, and chiefly to ladies' and children's bathing caps.

The purpose of a bathing cap is to keep the wearer's hair dry, and for such purpose the cap 5 requires to be close fitting at all portions of the circumference of the cap where it fits over the forehead and over the ears and around the back of the head. When the cap is made of india-rubber, the cap will adapt itself to the shape of 10 the head and lie fairly close, but will not always make the cap water-tight.

This invention has for its object to provide means fitted to, or integral with a bathing cap, whereby, when the cap is in use, water cannot 15 enter the cap.

According to the invention, the cap, made either of india-rubber or of other waterproof material, is provided with an endless inflatable rubber tube 20 of relatively large diameter and normally flat section, which tube extends all round the cap near to its lower edge and follows the contour of such edge, the tube being either held to the cap and in position by rubber solution, or being integral with the material of the cap. At a point 25 at one side of the cap, said tube is furnished with a short length of small-bore rubber tubing, whereby the tube may be inflated with air from the wearer's mouth when the cap is on the wearer's head, and be thereby caused to adapt itself to 30 the shape of the wearer's head and firmly hold the cap in position, as well as seal all entrances to the interior of the cap. To retain the air after inflation of the tube, the tubing is provided with a removable tapered peg or plug fitting its free 35 end.

After inflation of the tube, the inflator tubing may be tucked into a suitable pocket outside the cap, or pushed up between the cap and the side of the wearer's head. On deflating the tube by 40 removing the peg or plug, the cap can readily be removed from the head.

The invention will be further described with the aid of the accompanying drawing, wherein:—

Fig. 1 is a side exterior elevation, and

Fig. 2 a vertical section of a bathing cap with one example of the invention applied thereto.

Fig. 3 is a cross-section of a part of Fig. 2.

Fig. 4 is a cross-section showing another example of the invention.

In Figs. 1, 2 and 3, *a* is the bathing cap usually made of sections of thin sheet rubber, joined or seamed to produce a single shell or body part. *b* is the usual chin strap. To the interior of the cap and near to but away from its lower edge is 55 applied the continuous or endless flat and rela-

tively large diameter thin rubber tube *c*, the tube being fixed by rubber solution or other suitable fixing medium, the connection in all cases being such that no space is left between the tube and the cap.

The tube is longitudinally formed to the contour of the lower edge of the cap prior to fixing, so that it will lie quite flat against the cap and present no puckers or protuberances.

Passing through the wall of the cap *a* and into 10 the tube *c* is one end (shown dotted in Fig. 1) of a length of small-bore inflator rubber tubing *d*, the connection being effected and sealed by a small rubber washer. At its free end, the inflator tubing is furnished with a small tapered 15 peg or plug *e*, which on insertion closes the tubing against the escape of any air from itself and the tube *c*.

On first applying the cap to the head, the tube 20 *c* is flat (deflated) as shown in Fig. 2, but on inflation it swells out, and, tending to become round, presses firmly against the side of the wearer's head, and, leaving no space between itself and the wearer's head, prevents the ingress of water, see Fig. 3.

On one side of the cap may be an open-ended 25 tubular holder *f* through which the tubing may be threaded and caused to lie in when not in use. Near its free end the tubing may have one part of a press-in fastener *g*¹ adapted to engage the 30 counter-part *g*², fixed to the side of the cap, see Fig. 1.

Instead of being separately formed and cemented to the cap, the tube *c* may, when the cap is 35 also made of india-rubber, be integral with the cap, see Fig. 4.

It will be noted that in each example of the invention (Figs. 3 and 4) the air tube is away from the lower edge of the cap, and when deflated presents little or no protuberance liable 40 to interfere with the easy placing of the cap on the head, or with its easy removal, without disturbing the wearer's hair. Further, that there is no valve mechanism in the air tube *c*, or even where the tubing *d* enters the tube *c*, all parts 45 which lie next the head being of a soft yielding nature. Again, by using only a small peg or plug to close the tubing *d*, the fittings are comparatively cheap to make and apply.

What I claim is:—

A bathing cap having on its interior surface and near to but away from its lower edge an endless inflatable rubber tube of relatively large diameter and of normally flat section, such tube extending all round the cap and following the 55

5 contour of the lower edge of the cap, and said cap also having a short length of small bore rubber inflator tubing which at one end passes through the wall of the cap and is connected to the rubber tube, and at its other end is fitted with a removable closure plug, an open-ended tubular holder fixed to the exterior of the cap, and through

which the free end of the inflator tubing may pass, and the complementary parts of a press-fastener fixed respectively to the inflator tubing and cap, whereby the free end of the tubing is firmly held to the cap when not in use, as set forth.

ERNEST SAMUEL ABRAM.
